UNITED STATES PATENT OFFICE.

PHILIPPE COMEAU, OF NEW BEDFORD, MASSACHUSETTS.

WEAVING SHUTTLE.

Application filed May 6, 1924. Serial No. 711,478.

To all whom it may concern:

Be it known that I, PHILIPPE COMEAU, a citizen of the United States of America, residing at New Bedford, in the county of

5 Bristol and State of Massachusetts, have invented a certain new and useful Improvement in Weaving Shuttles; and I do hereby declare that the following is a full, clear, concise, and exact description of the invention, such as will enable others skilled in the art to which it appertains to make and use the same.

This invention relates to improvements in weaving shuttles, having for an object to 15 provide a novel and efficient form of thread guide for shuttles, whereby the thread carried thereupon can be quickly and conveniently directed to the eye thereof and brought to a position with relation to said eye, whereat it may be passed or "threaded" 20 through the same in a time much less than that required for "threading" operations with the now prevalent types or designs of shuttles.

25 It is likewise an object of the invention to provide a device of the character mentioned which, in addition to facilitating the "threading" of the shuttle eye, will provide an effectual tensioning means for the thread, 30 causing the same to be evenly removed from the bobbin.

Other objects of the invention will be in part obvious, and in part pointed out hereinafter.

35 In order that the invention and its mode of operation may be readily understood by persons skilled in the art, I have in the accompanying illustrative drawings, and in the detailed following description based 40 thereupon, set out one possible embodiment of the same.

In these drawings:—

Figure 1 is a fragmentary side elevation of a shuttle equipped with the invention; 45

Figure 2 is an enlarged fragmentary perspective view of such a shuttle;

Figure 3 is an enlarged fragmentary detail in section taken on the line 3—3 of Figure 1;

50 Figure 4 is an enlarged fragmentary detail in section taken on the line 4—4 of Figure 1; and,

Figure 5 is a reduced top view of the same.

55 Having more particular reference to the drawings, in connection with which like

characters of reference will designate corresponding parts throughout, 1 represents the shuttle proper having the usual pivotally mounted spindle 2 therein adapted to receive a bobbin such as indicated at 3, upon the same. One portion of the shuttle 1 is chambered or recessed as indicated at 4, such chambered portion 4 being disposed longitudinally of the shuttle proper 1 as is clearly shown in the Figures 2 and 5, the outer portion thereof being enlarged as indicated by the numeral 5, and having the lower portion thereof communicating with a longitudinally disposed reduced way 6. 60 An eye 7 is received in an adjacent portion of the shuttle proper 1, transversely of the same, as indicated in the Figures 1 and 2 and is positioned adjacent to the inner end of said longitudinally disposed reduced 65 way 6.

From the foregoing, it will be seen that a tortuous path of communication is established as between the spindle and bobbin receiving chamber or pocket of the shuttle 1 and the eye 7, whereby the thread 8 from 70 said bobbin 3 may be passed into and through or "threaded" through the eye 7.

With a view towards providing effectual 75 guide means for the thread 8 from the bobbin 3 in order that the same may be directed to a position adjacent to the eye 7 whereby to facilitate quick or convenient threading of the latter, I provide a guide indicated in its entirety by the numeral 9.

This guide 9 consists of a single length of wire or similar pliable or bendable material, but which possesses sufficient rigidity as to ensure its remaining in proper form subsequently to bending or shaping of the same. 80

The guide 9, as will be noted upon reference to the Figures 2 and 5, is disposed longitudinally of the chamber 4, having its inner end bent at substantially right angles whereby to provide an anchoring arm or portion 10 adapted to be embedded in an adjacent portion of the bottom of the chamber 4. An arm 11 is bent diagonally downwardly and rearwardly from the body portion of said guide 9 and as shown in the Figures 1 and 2, this arm is passed through a way 12 opening onto that side of the shuttle proper 1 receiving the eye 7, whereupon it is extended in substantial parallelism to said side of the shuttle proper 1 and is outwardly bent and substantially upon itself as indicated by the numeral 13. A 105 110

portion of this outwardly bent part of the arm 11, as shown in the Figures 1 and 2, is extended across the eye 7, whereupon the free end of the arm is formed with a right 5 angularly disposed anchoring finger 14 engaged or embedded in an adjacent portion of the side of the shuttle proper 1.

In this connection, it is to be noted that the forwardly disposed portion of the outwardly bent part 13 is directed through the way or opening 12 to a point wherat the same registers or aligns with the reduced longitudinal way 6, the purpose of which 10 will be subsequently described.

15 In order that the eye 7 and that portion of the arm 11 adjacent the same will not interfere with free movement of the shuttle 1 during operation of the same, I may and preferably do recess that side portion of 20 said shuttle receiving the same in the manner as indicated by the numeral 15, thus permitting the outer end or portion of the eye 7 and the outwardly bent portion 13 of the arm 11 to be inset with respect to the 25 side of the shuttle 1 receiving the same.

The eye 7 is preferably made of porcelain as is indicated upon the drawings, having a thread receiving slot communicating at its lower end with the inner end of the reduced longitudinal way 6. This way 6 also lies horizontally of the bobbin as its outer end terminates at one side thereof and its inner end communicates with the bottom of the vertically and longitudinally extending recess 4. The medial portion of the wire 9 forms a loop shaped guide finger lying longitudinally within the enlarged portion 5 of the recess 4 whereby the thread will be directed from the recess 4 into the 30 way 6, but this wire does not extend into the way 6. Therefore, this wire 9 only forms a guide in so far as it permits the making of a loop in the thread and guiding the latter from the recess 4 to the way 6, but 35 the particular configuration of the walls of the recess 4 and the way 6, as shown, causes the thread to be finally threaded within the eye 7.

The modus operandi of my improved 40 shuttle is as follows:

To thread the eye 7, a portion of the thread 8 is removed from the bobbin 3 and is passed along one side of the guide 9 as is indicated in the Figure 2, whereupon 45 the thread is looped and moved downwardly over the arm 11 to a position adjacent the opening or way 12, whereupon the free portion of said thread 8 is engaged or passed through the opening 12 so that the same 50 may be engaged by the hand of an operator and then drawn through the reduced longitudinal way 6 so that the same will be brought into the thread receiving groove or way of the eye 7, it being borne in mind

that the eye 7 communicates with the adjacent end of said way 6 and in consequence, permits the ready passing or "threading" 65 of said thread through the eye 7. During this "threading" operation, it will be seen that the guide 9 will serve as an effectual means for carrying the span of thread 8 forwardly and then downwardly 70 to a position adjacent the opening 12, whereupon, with passage of the free portion of said thread through the opening 12, it may 75 be engaged and then drawn through the way 6 and "threaded" with respect to the eye 7.

By usage of my improved "threading" 80 device, an operator is permitted to effectually thread the shuttle eye in a time much less than that required in the "threading" operations of shuttles now prevalent in this art and furthermore, it will be understood that the effort expended during such a 85 "threading" operation will be minimized.

Manifestly, the construction shown is capable of considerable modification, and such modification as is within the scope of 90 my claim, I consider within the spirit of my invention.

I claim:—

The combination with a shuttle having a bobbin receiving chamber and a thread receiving and guide chamber communicating therewith, said guide chamber being disposed longitudinally of one end portion of the shuttle and formed with a constricted intermediate portion in proximity to its point of communication with the bobbin 95 chamber, the opposite portion of said chamber being enlarged and having one part thereof opening transversely onto one side of the shuttle, such opening onto said side of the shuttle having a constricted longitudinal way extending therefrom, a shuttle eye positioned in said side of the shuttle having its thread receiving recess 100 communicating with said way, and the thread guide finger formed of a single piece of 105 material having one end thereof anchored in the guide chamber adjacent its point of communication with the bobbin chamber and disposed longitudinally of such guide chamber, the outer part of said finger being 110 bent downwardly and at angles upon itself and disposed in that portion of the same opening transversely onto said side of the shuttle, the free end of the finger being disposed in substantial parallel relationship to 115 an adjacent portion of said side of the shuttle and arranged in proximity to the constricted longitudinal way and said shuttle eye.

In witness whereof I have hereunto set 125 my hand:

PHILIPPE COMEAU.
